ATTORNEY

UNITED STATES PATENT OFFICE.

THOMAS J. DUDLEY, OF DALLAS, TEXAS.

DRAFT-EQUALIZER.

1,109,908.

Specification of Letters Patent.

Patented Sept. 8, 1914.

Application filed December 31, 1913. Serial No. 809,633.

To all whom it may concern:

Be it known that I, THOMAS J. DUDLEY, a citizen of the United States, residing at Dallas, in the county of Dallas and State of Texas, have invented certain new and useful Improvements in Draft-Equalizers, of which the following is a specification.

My invention relates to a new and useful draft equalizer.

10 Its object is to provide a draft equalizer which will permit either three horses to travel at one side of the beam and two at the other, or three horses at one side of the beam and one at the other.

15 A further object is to provide a draft equalizer that may be readily adjusted to compensate for the different draft powers of different horses.

Finally the object of my invention is to 20 provide a device of the character described, that will be strong, durable, simple and efficient and comparatively easy to construct, and also one the various parts of which will not be likely to get out of working order.

25 With these and various other objects in view, my invention has relation to certain novel features of the construction and operation, an example of which is described in the following specification, and is illustrated in 30 the accompanying drawing, wherein:

Figure 1 is a plan view showing my equalizer mounted upon the wheeled frame of a vehicle. Fig. 2 is a sectional view of the same taken upon the line $v-v$ of Fig. 1. Fig. 3 is another sectional view taken upon the line $w-w$ of Fig. 1. Fig. 4 is a detail transverse sectional view taken upon the line $x-x$ of Fig. 1. Fig. 5 is a detail section taken upon the line $y-y$ of Fig. 1. Fig. 6 40 is a detail section taken upon the line $z-z$ of Fig. 1. Fig. 7 is a detail section taken upon the line $a-a$ of Fig. 1.

Referring now more particularly to the drawing, wherein like reference characters 45 designate similar parts in all the figures, the numerals 1, 2 and 3 respectively denote the axle, wheels and beam of a vehicle. Upon the front end of the beam 3, there is eccentrically pivoted a lever 4 transverse of 50 said beam. In front of the lever 4, in a spaced and parallel relation to said lever, there is mounted a second lever 5 substantially equal in length to the lever 4, and supported from the extremity of the longer arm 55 of the lever 4 by a pair of bars 6 respectively engaging the top and bottom of the lever 4

in a spaced relation. The bars 6 converge as they extend forwardly, and engage between their forward ends one extremity of the lever 5, which lever is free to pivot about its connection with the bars 6. The pivoted extremity of the lever 5 is engaged between an upper and lower bar 7, the bars 7 being pivoted upon the lever 5 adjacent to the center 7^a of said lever. The bars 7 project 60 beyond the correlated extremity of the lever 5 and engage rigidly between their projecting portions one end of a member 8 normally aligned with the lever 5. From that extremity of the member 8 to which the bars 7 are secured, a pair of swinging links 9 are extended rearwardly and are made to engage between their rear ends the outer extremity of an arm 10, pivoted at its other extremity at the center of the lever 4. In their 65 normal positions the members 4 and 10 will have a parallel relation. To the arm 10 there is intermediately secured the forward extremity of a chain 11 which is fastened 70 at its rear end to the axle 1.

Upon that extremity of the lever 5 which lies in front of the short arm of the lever 4, there is mounted a bracket 12 formed with upper and lower flanges 13, and a pair of intermediate flanges 14. The lever 5 is engaged between the lower flanges 13 and 14, and is held in such engagement by a vertical pin 14^a passing through all four flanges of said bracket. A lever 15 is eccentrically pivoted upon the pin 14^a, 80 said lever being engaged between the upper flanges 13 and 14 of the bracket 12. In its normal position, the lever 15 is parallel to the axle 1, its longer arm being extended above the lever 5 along the entire 85 length thereof, and its shorter arm projecting some distance beyond that extremity of the lever 5 which carries the bracket. Between the middle flanges 14, a pulley 16 is rotatably mounted upon the pin 14^a, the 90 function of said pulley being made clear 95 hereinafter.

Upon the free extremity of the short arm of the lever 15, there is mounted a bracket 17 formed with top and bottom flanges 18 and an intermediate flange 19. The lever 15 is engaged between the upper flange 18 and the intermediate flange 19, and is held in such engagement by a vertical pin 19^a passing through all three flanges and 100 through said lever. Between the flange 19 and the lower flange 18, a pulley 20 is rota- 105 110

tably mounted upon the pin 19^a, the function of said pulley being hereinafter explained.

Upon the short arm of the lever 4, there is rigidly mounted an angular bracket 21, having a rearwardly projecting end upon which is pivoted one extremity of a short lever 22, normally parallel to the axle. From the free extremity of the lever 22 a chain 23 is extended to the axle and secured thereto adjacent to its point of connection with the beam. To the lever 22 is intermediately secured one end of a swinging link 23^a, substantially parallel to the beam 3, the other end of said link being pivoted intermediately upon a short lever 24 mounted pivotally upon the bracket 21. From the free extremity of the lever 24, a chain 26 is extended forwardly and is passed around the pulley 16. From the pulley 16 the chain 26 is extended to the rear of the pulley 20 passing around said pulley and then extending forwardly. At its forward extremity, said chain has an intermediate connection with a double-tree 27 carrying a pair of swingle-trees 28 swingingly mounted upon its extremities.

At its outer extremity, the member 8 has connection through a forwardly extended chain 29 with a double-tree 30 to the extremities of which there are swingingly secured a pair of swingle-trees 31.

To that extremity of the lever 15 which is disposed above the bars 7, there is secured a forwardly extending chain 32 having connection at its forward end with a swingle-tree 33. The swingle-trees 28 lie to the right of the center line of the vehicle while the swingle-trees 31 and 33 lie to the left of said center line.

When it is desired to use my equalizer with four horses instead of five, a swingle-tree 34 is substituted for the double-tree 27, and the members 32 and 33 are shifted to the position indicated in Fig. 1 in dash lines at 35 and 36. The members 29 and 31 are also shifted to the position indicated in Fig. 1 in dash lines by the numeral 37 and 38.

What I claim is:

1. A draft equalizer, comprising a lever transversely pivoted upon the beam of a farm implement, a second lever spaced in front of the first lever, and pivotally supported by the same, a third lever pivoted upon the second lever, a fourth lever pivotally connected with the second lever and normally alined with the same, a fifth lever pivoted upon the first lever, and projecting

beyond one end of the same, a swinging link extending between the free end of the fifth lever and the fourth lever, a flexible connection between the fifth lever and some portion of the farm implement, and whiffle-trees respectively connected with the outer end of the fourth lever and with the end portions of the third lever.

2. A draft equalizer comprising a lever transversely pivoted upon the beam of a farm implement, a second lever spaced in front of the first lever and pivotally supported by the same, a third lever pivoted upon the second lever, a fourth lever pivotally connected with the first lever and normally alined with the same, a fifth lever pivoted upon the first lever and projecting beyond one extremity of same, a swinging link connecting the free end of the fifth lever with the fourth lever, a flexible connection between the fifth lever and some portion of the farm implement, a flexible connection between the first lever and some portion of the farm implement, a flexible connection between the first and second lever having a portion extending longitudinally upon the third lever, and adapted to move longitudinally relative to the same, and having a portion extending forwardly from the third lever, and whiffle-trees respectively connected to the forward end of said flexible connection, to the third lever, and to the outer end of the fourth lever.

3. A draft equalizer comprising a lever eccentrically pivoted upon the beam of a farm implement, a second lever spaced in front of the first lever and pivotally supported at one of its extremities by the longer arm of the first lever, a third lever pivoted upon the free end of the second lever, and projecting beyond said end, a fourth lever pivotally connected with the pivoted end of the second lever, and normally alined with the second lever, means limiting the angular displacement of the fourth lever, a flexible connection between the short arm of the first lever and the adjacent end portion of the third lever and whiffle-trees respectively having connection with the outer end of the fourth lever and the end portions of the third lever.

In testimony whereof I have signed my name to this specification in the presence of two subscribing witnesses.

THOMAS J. DUDLEY.
